IRMFRIED KIRSTAEDTER, OF BERLIN, GERMANY, ASSIGNEE TO SIEMENS & HALSKE,
AKTIENGESELLSCHAFT, OF SIEMENSSTADT NEAR BERLIN, GERMANY, A CORPORATION OF GERMANY

AMPLIFIER POWER SUPPLY

Application filed July 18, 1930, Serial No. 468,806, and in Germany June 17, 1929.

The present invention relates to apparatus for amplification and rectification of signal currents, supplied with energy from networks.

5 Amplifiers which are supplied from a supply line, or power network, and after having been connected with the latter, require a certain length of time until the cathodes of the amplifier tubes have been heated to the 10 temperature where electron emission is initiated. This phenomenon becomes particularly noticeable with tubes employing indirectly heated cathodes. It is also noticeable in tubes employing directly heated cathodes, if the cathode current is derived from a rectifier also taking a certain length of time 15 for getting started. The same condition has been observed in devices including low-pass filters designed to smooth the direct current 20 and rid it of stray components.

But, this defect is particularly apparent and serious, in the case of indirectly heated tubes employed in an amplifier utilized as part of an order, or safety signal, equipment. Such order, or control, systems consist, for instance, of a microphone at the transmitter end and a loudspeaker for rendering the orders or signals, audible, the network supply means, or power pack, being inserted between these two parts of the equipment. In order to secure immediate operation, it is essential to permanently maintain the amplifier circuit, and this would involve a relatively great wear and tear in tubes, and 30 excessive current consumption.

Now, according to the present invention practically instantaneous operation is insured with considerably reduced current consumption and tube depreciation, by employing 40 means adapted to reduce the cathode temperature for the time the installation is held in readiness for operation. A device of this kind may have the form of a switch inserted in the filament circuit which in one of its positions cuts a resistance in the circuit. It is preferable to provide the switch with three 45 stages or steps, one step each being for complete cutting in, and out, of circuit, while the third position cuts the resistance in the 50 filament circuit during the periods where

the device is held in readiness. In this manner it is possible to pre-heat the amplifier tube cathodes, by means of the series resistance, to a point where it is ready for actual 55 operation within a few seconds' time, after connection.

The novel features which I believe to be characteristic of my invention are set forth with particularity in the appended claims, the invention itself, however, as to both its 60 organization and method of operation will best be understood by reference to the following description taken in connection with the drawing in which I have indicated diagrammatically one arrangement whereby 65 my invention may be carried into effect.

In the drawing,

Fig. 1 shows diagrammatically a circuit including the invention; and,

Fig. 2 shows a detail view of the switch 70 means.

Referring to Fig. 1, M denotes a microphone which is connected with a loudspeaker L by means of an amplifier V, energized by a power pack, or network supply. The amplifier V is connected with the alternating current supply line N through two paths comprising the switch S and the resistance R. The switch is illustrated in further detail in 75 Fig. 2.

In position A, the power pack amplifier V is disconnected from the current source N, since the contact springs 1 and 2 are opened. In position E, by closing the contact springs 3, 4, 5, the resistance R is a short-circuited 80 while the amplifier and the power pack are connected to the full supply voltage. In position B, denoting the pre-heating condition, contacts 3, 4, 5 are opened, while the resistance R is cut in the circuit by closing the contacts 1 and 2.

While I have indicated and described one arrangement for carrying my invention into effect, it will be apparent to one skilled in the art that my invention is by no means limited to the particular organization shown and described, but that many modifications may be made without departing from the scope of my invention as set forth in the appended claims. 95

What I claim is:

1. In an amplifier circuit which includes at least one electron discharge relay provided with a cathode of the type having an inherent delay characteristic of such duration 5 as to make appreciable the length of time required for the relay to assume normal operation after the application of energizing potentials thereto, a cathode energizing circuit including a source of current for supplying electrical energy at a voltage best adapted for normal operation of the electron relay when normal operation thereof is desired, means adapted to be connected to the cathode energizing circuit for reducing the voltage 10 of the energy supplied to the cathode energizing circuit from said source to a value insufficient for normal operation of the relay device but sufficient to maintain the cathode at such a state of energization that it will 15 assume normal operation characteristics substantially contemporaneous with the application of normal voltage values to the circuit, said means comprising a fixed resistance element adapted to be placed in and out of the 20 cathode energizing circuit by means comprising a switch having two sets of contacts and a contact operating element, said contact operating element being adapted to close either set of contacts, means for connecting the 25 cathode energizing circuit directly across the source when one of said sets of contacts is closed by said element so as to impress the normal operating voltage across said circuit, and means for connecting the source and said 30 cathode energizing circuit through the re-

sistance device when the other set of contacts is closed by said element so as to impress the reduced voltage across the circuit.

2. In an amplifier circuit which includes at least one electron discharge relay provided with an indirectly heated cathode, an energizing circuit for said cathode including a source of current adapted to supply electrical energy to said energizing circuit at a voltage best adapted for normal operation of the electron relay, means comprising an impedance element adapted to be included in the cathode energizing circuit for reducing the voltage of the energy supplied from said source to the cathode energizing circuit to an intermediate value said value being insufficient for normal operation of the relay device but sufficient to maintain the cathode at such a state of energization that it will assume normal operation characteristics substantially contemporaneously with the application of normal voltage to the cathode energizing circuit, and a selector device in cooperative relation with the cathode energizing circuit for alternatively rendering the impedance element inoperative to control the operation of the relay during desired periods of normal operation of relay and rendering the impedance element operative to reduce the voltage of the electrical energy applied to the cathode energizing circuit to said intermediate value. 70 75 80 85 90 95

In testimony whereof I affix my signature.
